UNITED STATES PATENT OFFICE.

JASPER K. ROBINSON, OF GRAVELLY, ARKANSAS.

DESIGN FOR A COMBINED SEAT AND DESK.

49,159.

Specification for Design.

Patented June 6, 1916.

Application filed November 20, 1915. Serial No. 62,653. Term of patent 14 years.

To all whom it may concern:

Be it known that I, JASPER K. ROBINSON, a citizen of the United States, residing at Gravelly, in the county of Yell and State of Arkansas, have invented a new, original, and ornamental Design for Combined Seats and Desks, of which the following is a specification, reference being had to the accompanying drawing, forming a part thereof.

The figure is a perspective view of a

combined seat and desk, showing my new design.

I claim:

The ornamental design for a combined seat and desk as shown.

JASPER K. ROBINSON.
